UNITED STATES PATENT OFFICE.

EDWARD THUEMLER, OF CHICAGO, ILLINOIS.

BICYCLE.

SPECIFICATION forming part of Letters Patent No. 398,195, dated February 19, 1889.

Application filed August 16, 1888. Serial No. 282,923. (No model.)

To all whom it may concern:

Be it known that I, EDWARD THUEMLER, a citizen of the United States, residing at Chicago, in the county of Cook and State of Illinois, have invented certain new and useful Improvements in Bicycles, &c., of which the following is a specification.

My invention relates to the seats of bicycles, tricycles, or other wheeled vehicles that are propelled by the rider. Its object is to arrange and support the seat or saddle in such a manner that its elevation may be adjusted or changed by the rider while he is mounted thereon, and even while the machine is in motion.

It consists of a seat or saddle resting on a support which may be adjusted vertically, and is held at any desired elevation by means of a spring-dog, friction-clamp, or any other suitable locking device that may be controlled or released by the rider.

The accompanying drawings show my invention as applied in one way to the present well-known safety-bicycle; but it might be adapted to other styles of machines, the details of construction varied in many ways that will readily suggest themselves to a skilled mechanic, and some of the parts used without the others, without departing from the spirit of my invention, as hereinafter set forth in the claims.

Figure 1 is a side elevation, partly in section, of a bicycle having my improved seat-support applied thereto. Figs. 2 and 3 are similar views of seat-standards detached, showing some of the modifications that may be employed in carrying out my invention.

It is known as the class of "safety-bicycles" in which there are two wheels, A A', of comparatively small diameter—say thirty inches. Mounted upon the axle of the rear wheel, A', is the supporting-frame B, pivotally connected at its front end to the bifurcated post B', which embraces the front wheel, A, and is mounted upon its axle. The crank-shaft C is mounted in suitable bearings in the lower part of the frame, so that the cranks C' attached to it pass close to the ground at the lower part of their revolution, and a sprocket-wheel, C², on the shaft is connected

by a suitable chain, C³, to a corresponding sprocket-wheel, C⁴, on the driving-wheel A'. The seat or saddle is located between the two wheels and nearly over the cranks, as is usual in this class of machines, in all or nearly all of which some provision is made to permit of the vertical adjustment of the seat. Usually this is accomplished by making the upright standard of the frame hollow and fitting therein a stud-post, upon the upper end of which the saddle is secured. The post slips up or down in the standard, and is held at any desired point by any suitable means, such as set-screws, friction-clamps, &c. With these devices, when the rider adjusts the elevation of his seat, he must be off the machine and has to employ a wrench, screw-driver, or some other tool to loosen the set-screw or clamp, and having once attained the desired elevation for his seat it is allowed to remain so permanently. This elevation is usually at such a point that when the cranks are at the lowest point of their revolution the rider's leg is straightened out and the foot depressed from the ankle-joint, so that the toes or ball of the foot will just reach the crank-pedal and the foot is still several inches from the ground, the full clearance allowed the crank—say from four to seven inches. If, therefore, the rider desires to stop his machine, it is necessary for him to dismount at once, as he cannot maintain the balance of a still machine and is unable to reach the ground with either foot.

Now it is the main purpose of my invention to obviate this difficulty by so mounting the seat that its vertical elevation may be adjusted and controlled at any time by the rider while mounted thereon, and when he desires to stop he can lower the seat until his feet will rest upon the ground, thus enabling him to remain seated on the saddle while the machine is standing still, to dismount therefrom when standing upon the ground, or remount and start it while standing and elevate the saddle to its normal position when sufficient headway is attained.

In Fig. 1 the standard D of the frame is hollow and closed at its lower end. The saddle-post D' fits into the upper end of the stand-

ard and also into the lower end of the sleeve E of the saddle-frame, which may be vertically adjusted on the post and locked in place by the set-screw e. The saddle-post D' is 5 provided at one side with a groove, d, in the bottom of which are two or more notches or recesses, d'. A detent or catch, F, is pivoted at f between the lugs f' on the standard D, and, projecting through an aperture, f², in the 10 standard, takes into the recess d' of the seat-post, where it is held by the spring f³. By pressing the lower end of the detent-lever toward the standard the upper end may be withdrawn from the recess d' in the post D', 15 but not from the groove d, the ends of which limit the movement of the post in the standard.

In order that the rider may trip the catch without removing his hands from the steering or handle bar G, I pivot a bell-crank lever, H, at h, between suitable lugs on the frame, one end of the lever resting against the lower end of the catch F and the other end connected by means of a suitable rod, I, 20 or flexible cord to the lever G', pivoted on the handle-bar at g in a manner similar to the ordinary brake-levers in general use. These brake-levers are usually on the right-hand end of the handle-bar, and my catch-lever can 25 be at its opposite or left-hand end.

When the machine is in use and the rider mounted thereon and moving, the saddle would be in the position shown in the drawings.

30 Should the rider desire to stop, he would press upon the lever G' and withdraw the catch from the lower recess, d', in the post and permit it to sink or "telescope" into the standard until his feet could touch the ground, 35 when he could remain astride of the machine or dismount with greater ease than from the saddle at its normal elevation. When the saddle is lowered, the catch will take into one of the upper notches and hold the post and 40 saddle at the desired height.

The machine may be started by the rider when the saddle is in this lower position, and when sufficient headway has been attained he may throw his entire weight upon the cranks, 45 relieving the saddle of its load, and then, by withdrawing the catch from the upper notch, permit the saddle to rise to its normal elevated position. This may be accomplished by the rider grasping and raising the saddle with 50 one hand, while he holds the catch out of engagement with the other; or it may be done by a spring applied beneath the saddle or post in any suitable manner, so as to lift them when released from the catch.

55 In Fig. 1 I show a spiral spring, J, of sufficient expansive force to lift the saddle and post, beneath which it stands, in the hollow standard of the frame.

In Fig. 2 of the drawings I show a modification of the mechanism for controlling the 60 catch F, which in this instance is pivoted be-

tween lugs at the back and near the top of the standard D, from which extends a handle, K, with a pivoted finger-piece, L, connected by a link, l, with the free end of the catch F. The 70 lengths of the handle and link are adjustable by means of the sleeve-sections K' l' to suit them to adjustments of the heights of the saddle, and they may be located beneath the saddle at its side or rear, as will be found most 75 convenient to the rider.

In Fig. 3 is shown another arrangement or modification of the parts. The post D projects from the top of the frame-standard and is rigidly attached thereto. The post is 80 grooved and notched, as before described, and a sleeve, M, is fitted to slide freely up and down thereon. A short post, N, attached to the saddle-frame, fits into the top of this sleeve, and is held at any desired elevation by 85 a set-screw, N'. A handle, K, with a pivoted finger-piece, L, is mounted on the sleeve and moves up and down with the saddle in a manner that will be obvious from an inspection of the drawings. 90

The seat may be raised by a spring, J, wound around the post D' and bearing against the lower end of the sleeve, or the spring dispensed with and the saddle raised by hand, 95 as before described.

What I claim as new and useful and of my own invention is—

1. In a bicycle, a seat having a supporting device whereby the seat may be adjusted vertically by the rider when mounted thereon, 100 with means under his control for locking it at any desired elevation, substantially as hereinbefore set forth.

2. The combination of a seat-supporting post, D', provided with notches d', the sleeve 105 or standard in which it is fitted, the spring detent-catch F, taking into the notches, and means whereby the rider when mounted on the seat may withdraw the catch from the notches, substantially as and for the purpose 110 hereinbefore set forth.

3. The combination of the seat-supporting post D', provided with a notched rack or series of recesses, the tubular sleeve in which it is fitted, the detent-catch pivoted to the 115 sleeve and taking into the notches of the rack, and a spring pressing upward to raise the seat when the detent is withdrawn from the rack, substantially as hereinbefore set forth. 120

4. The combination of the seat-supporting post provided with a groove, d, and notches d', the tubular sleeve in which it is fitted, the spring detent-catch pivoted to the sleeve and taking into the groove and notches, and the 125 spring pressing upward to raise the seat, substantially as hereinbefore set forth.

5. In a bicycle, the combination of the seat-supporting post D', with its series of notches, the sleeve-standard into which it is fitted, the 130 spring detent-catch pivoted to the sleeve and taking into the notches in the post, and the

trip-lever G', pivoted on the steering-handle G of the bicycle and connected by suitable mechanism to the detent-catch, whereby the latter may be withdrawn from engagement with the notches in the seat-post, substantially as and for the purpose hereinbefore set forth.

In testimony whereof I affix my signature in presence of two witnesses.

EDWARD THUEMLER.
